ABSTRACT: A setting tool suitable for installing lead anchors in walls having the following elements: a main body having a tapered conical nose at one end and a central bore having an enlarged diameter section at the end opposite the nose. An annular groove is cut in the surface of the main body concentric to the central bore, and a small bore extends from the bed of the groove to the central bore on an axis transverse to the axis of the central bore. A drive bolt is seated in the central bore of the main body, and comprises a cylindrical head having an internal recess adapted to receive a turning wrench, a section of reduced diameter attached to and on the same axis with the head having an annular groove in it which is aligned with the annular groove on the surface of the body, and a threaded section attached to the section of reduced diameter and having the same axis. A pin is seated in the small bore in the main body, one end of which extends into the annular groove in the section of reduced diameter of the drive bolt, thus retaining the bolt against axial movement. A retaining split ring, mounted in the groove of the body, holds the pin in place.

ATT'YS.

LEAD ANCHOR-SETTING TOOL

BACKGROUND OF THE INVENTION

1. Field of the Invention

This invention relates to a setting tool for lead or other expandable metallic anchors. Lead anchors are conventionally used to provide supporting means in a wall for bolts, hooks, and the like, where access cannot be gained to the interior of the wall to mount a conventional nut and bolt type anchor.

2. The Prior Art

A lead anchor is mounted by placing it in a close fitting orifice in a wall, then expanding the anchor against the walls of the orifice to achieve a tight, secure fit. In the past, when lead anchors were installed in walls, the anchors would sometimes fall in the stud spaces behind the walls because there has been no good way to hold the anchors securely while installing them in the walls. Once an anchor fell into the stud space there was no economical way to get it out. The only way to get it out was to cut a hole in the bottom of the wall. The cost of repairing the hole was more than the cost of the lead anchor.

It is an object of this invention to provide a setting tool for inserting lead anchors in walls.

It is a further object of this invention to provide a setting tool for inserting lead anchors in walls which enables an anchor to be held securely while it is being put in place.

Other objects of this invention will appear in the following description and appended claims, reference being had to the accompanying drawings forming a part of this specification wherein like reference characters designate corresponding parts in the several views, in which:

FIG. 1 is an exploded perspective view of the tool of the invention;

FIG. 2 is a side elevational view of the tool of the invention, showing it in operative position; and

FIG. 3 is a front elevational view of the tool of the invention, showing the operative wrenches in position.

DESCRIPTION OF THE PREFERRED EMBODIMENT

The setting tool 10 of this invention consists of a main body 12, preferably formed from hexagonal stock. The body 12 has a tapered conical nose 14 and a central bore 16 having an enlarged diameter section 18 at the end opposite the nose 14. The body 10 also has an annular groove 20 around the end adjacent the nose 14 and a small bore 22 extending from the bed of the groove 20 to the central bore 16, having an axis transverse to the axis of the central bore 16.

A drive bolt 24 having a threaded end 26, an enlarged diameter section 28 having an annular groove 30 in it, and a still further enlarged diameter head 32 with a hexagonal shaped internal recess 34 for receiving a wrench head, is seated in the central bore 16 of the body 12. The groove 30 in the enlarged diameter section 28 is positioned so that when the drive bolt 24 is in place within the body 12, it is in concentric radial alignment with the groove 20 in the body 12. When the drive bolt 24 is seated within the main body 12, a pin 36 is inserted in the small bore 22, engaging the groove 30 in the enlarged diameter section 28. A retaining split ring 38 is then seated in the groove 20, holding the pin 36 in place, thus retaining the bolt 24 against axial movement.

In use, an anchor 40 (not a part of the invention) comprising a tubular outer member 42 and a conically shaped inner member 44 having a threaded central bore 46, is threaded onto the threaded end 26 of the bolt 24 seated in the body 12. The base of the conical shaped inner member 44 is greater in diameter than the interior diameter of the outer member 42. The anchor 40 is then placed in position in an orifice 48 in a wall 50. A wrench 52 is then placed around the main body 12 and an Allen wrench 54 is inserted in the recess 34 of the bolt 24. The split ring 38 serves as a support for the wrench 52. The bolt 24 is then rotated while the body 12 is held steady. Rotating the bolt 24 draws the inner member 44 of the lead anchor 40 toward the tool 10 while the conical nose 14 of the

body 12 is drawn toward the outer member 42. Drawing the inner member 44 of the anchor 40 toward the bolt 24, causes the outer member 42 to expand at both ends, seating the anchor 40 tightly within the wall 50. The expansion at the rearward end of the anchor 40 is due to the pressure of the inner member 44 on the outer member 42 while the expansion at the forward end is due to the pressure of the conical nose 12.

It should be appreciated that the size of the tool 10 as well as the size of the bolt 24 can be varied to enable practically any size lead anchor to be installed. The dimensions of the parts need only be such that the bolt 24 can be seated in the main body 10, and that the threaded end 26 of the bolt fit the inner member 44 of the anchor 40.

I claim:

1. A setting tool suitable for installing lead anchors in walls comprising an elongate main body having a conical nose portion at one end, means defining a central bore extending longitudinally through said body, and opening centrally of said nose portion, a drive bolt mounted for free rotation within said bore, means maintaining said drive bolt against axial displacement in said bore, said bolt having a threaded portion projecting from said bore, beyond said nose portion and coaxially aligned therewith, and adapted to be threadably received by the inner member of the anchor and the distal end of said conical nose portion adapted to be received within the adjacent opening of the outer member of the anchor, whereby rotation of said drive bolt, while said main body is held steady, draws the inner member of the anchor toward the tool, concurrently thereby expanding the outer member of the anchor against an orifice in a wall, thus securing the anchor in the wall.

2. A setting tool suitable for installing lead anchors in walls, comprising an elongate main body having a tapered conical nose portion at one end, means defining a central bore extending longitudinally in said main body having an enlarged diameter section at the end opposite said nose portion, means defining a small bore extending transversely through said body to said central bore, a drive bolt seated in said central bore for free rotation having a threaded cylindrical body section extended beyond said nose portion, an enlarged cylindrical neck section having an annular groove therein attached to one end of said body section, a still further enlarged cylindrical head attached to said neck section, said head being adapted to receive a turning means, the body section, neck section and head all being on the same axis, a pin seated in said small bore, an end of which extends into said annular groove in said section of reduced diameter, thereby retaining said bolt against axial movement, and means for holding said pin in place, said threaded section of said drive bolt adapted to be received within the inner member of an anchor and said conical nose portion adapted to be received within the outer member of the anchor, whereby rotation of said drive bolt draws the inner member of the anchor toward the tool and expands the outer member.

3. A setting tool suitable for installing lead anchors in walls, comprising an elongate hexagonal shaped main body having a tapered conical nose at one end, means defining a central bore extending longitudinally in said main body having an enlarged diameter section at the end opposite said nose, an annular groove on the surface of said body concentric to said central bore, means defining a small bore extending transversely through said body from said groove to said central bore, a drive bolt seated in said central bore for free rotation, having a threaded cylindrical body section, an enlarged cylindrical neck section having an annular groove therein attached to one end of said body section, a still further enlarged cylindrical head attached to said neck section, said head having a recess in the top thereof adapted to receive a turning means, the body section, neck section and head all being on the same axis, a pin seated in said small bore, an end of which extends into said annular groove in said section of reduced diameter, thereby retaining said bolt against axial movement, and a

4. A setting tool suitable for installing lead anchors in walls, comprising an elongate hexagonal shaped main body having a tapered conical nose at one end, means defining a central bore extending longitudinally in said main body having an enlarged diameter section at the end opposite said nose, an annular groove on the surface of said body concentric to said central bore, means defining a small bore extending transversely through said body from said groove to said central bore, a drive bolt seated in said central bore for free rotation, having a threaded cylindrical body section, an enlarged cylindrical neck section having an annular groove therein attached to one end of said body section, a still further enlarged cylindrical head attached to said neck section, said head having a recess in the top thereof adapted to receive a turning means, the body section, neck section and head all being on the same axis, a pin seated in said small bore, an end of which extends into said annular groove in said section of reduced diameter, thereby retaining said bolt against axial movement, and a

3,600,789

3

retaining ring, mounted in said groove of said body, holding said pin in place, said threaded cylindrical body section projecting from said central bore beyond said nose and adapted to be threadably received by the inner member of the anchor and the tapered conical nose adapted to be received within the adjacent end of the outer member of the anchor, whereby rota-

4

tion of said drive bolt while said main body is held steady draws the inner member of the anchor toward the tool, concurrently thereby expanding the outer member of the anchor against an orifice in a wall, thus securing the anchor in the wall.
